UNITED STATES PATENT OFFICE.

JOHN C. FEBIGER, JR., OF NEW ORLEANS, LOUISIANA.

WATER-CLOSET.

SPECIFICATION forming part of Letters Patent No. 556,178, dated March 10, 1896.

Application filed June 7, 1895. Serial No. 551,981. (No model.)

To all whom it may concern:

Be it known that I, JOHN C. FEBIGER, Jr., of New Orleans, parish of Orleans, State of Louisiana, have invented certain new and useful Improvements in Water-Closets, of which the following is a specification, reference being had to the accompanying drawings.

The object of my invention is to produce improvements in devices for attaching seats 10 to water-closet bowls in order to prevent the breaking or chipping of parts of the bowl to which the seat is attached.

One of the objects in the construction of sanitary closets has been to reduce the seat- 15 surface, but heretofore in articles of this class devices for securing the seat to the bowl have proven defective, owing to the fact that the means of attaching the seat to the bowl has been a rigid one, so that when the front buf- 20 fer-rubbers get hardened or compressed by use the rear buffer-rubbers act as a fulcrum, producing a strain upon the connection be- 25 tween the seat and the bowl, which breaks the bowl at the place of connection.

25 In the accompanying drawings, Figure I is a side elevation of a closet bowl and seat embodying my invention. Fig. II is a rear sec- 30 tional view of the same, taken on the line 2 2 of Fig. I and looking toward the bowl. Fig. III is a group of details illustrating the lug- 35 plate and pad.

Referring to the figures on the drawings, 1 indicates a closet-bowl made of any suitable and ordinary frangible material—as, for ex- 35 ample, china or porcelain. It may be made in any ordinary style or design with any pre- 40 ferred form of vents, or similar, usual or pre- 45 ferred arrangements. It is provided with a rear extension or projection 2 of suitable 50 shape and dimensions, through which the 55 flush-water supply-bore may be introduced, as indicated at 3. It is provided upon oppo- 60 site sides with parallel vertical surfaces 4.

55 indicates an ordinary seat-block or that 45 portion of the seat which in practice is secured to the bowl and is usually made of wood.

6 indicates the seat hinged, as indicated at 7, to the seat-block.

8 indicates the plane of division between 50 the seat-block and the seat.

9 indicates the usual hinged cover or lid.

10 indicates the rear buffers, consisting

usually of rubber knobs, and 11 a similar front buffer.

12 indicates each of a pair of bracket-pieces 55 which are secured, respectively, as by screws 13, to the bottom of the seat-block, and whose legs 14 extend opposite to each other along the surfaces 4 and in close proximity thereto.

15 indicates abutment thumb-screws, one 60 of which works in a screw-threaded aperture in each of the legs 14, preferably near its lower extremity.

16 indicates a vertical recess or slit in the end of each of the legs 14 and in vertical ra- 65 dial alignment with the screw 15.

17 indicates each of two oblong vertically-disposed recesses located upon opposite sides of the projection 2 and sunk through the surfaces 4 thereof. 70

18 indicates lug-plates that fit within the recesses 17, respectively. They are somewhat shorter than the recesses, so as to provide a space 19 between their upper ends and the upper ends of the recesses, respectively. 75

20 indicates a lug on each of the lug-plates, which works in the slit 16 of the leg 14.

21 indicates a pad of rubber or suitable yielding material, which is designed to afford between the lug-plate and the bottom of its 80 recess in the projection 2 a yielding cushion or compensating connection against vertical strain.

The surfaces of the recesses 17 and the lug- 85 plates 18, which are opposed to the sides of the pad, are rendered suitably abrasive or roughened, as by knurling or checking.

In practice the lower surfaces of the seat-block 5 and the seat 6 are brought into exact alignment, so that the buffers 10 and 11 90 squarely touch and rest upon the edge of the bowl 1 and without strain at the plane 8. In this position the abutment-screws 15 are screwed against the lug-plates 18, so as to fix the parts in the position to which they are 95 adjusted, the legs 14 being held firmly in the vertical position by the engagement of the abutment-screws 15 with the lug-plates and the engagement of the sides of the slits 16 with the lugs 20. All necessary range of ad- 100 justment between the legs 14, which carry the seat-block 5, and the lug-plates, which hug the projection 2, is obtainable through the depths or lengths of the slits 16.

When properly adjusted, as above described, the buffers 10 and 11 sit squarely upon the edge of the bowl, and if at any time thereafter, through permanent or temporary compression of the buffers or unequal compression of the buffers 10 and 11, a strain is exerted at the plane 8 between the seat-block and the seat, or upon the buffers 10 as a fulcrum the strain is not communicated to the fragile material of the bowl but is taken up and dissipated through the pads 21, the space 19 permitting the requisite longitudinal or vertical movement of the lug-plates 18 to which the parts that exert the strain are secured.

It will be seen that by reason of the close connection or contact between the pad 17 and the plate 18 the latter under strain will cause the pad to yield edgewise, or, if you please, vertically, but will resume its normal position by reason of the resiliency of the pad when the strain is removed. If, however, the strain is greater than can be compensated for by the yielding of the pad, the connection between the brackets depending from the seat and the plates will be broken, accomplishing the detachment of the parts without bringing the direct strain upon the frangible material of which the bowl is composed.

I am aware of the fact that a patent has been granted to one W. S. Cooper, No. 385,163, dated June 26, 1888, for a device analogous to my invention in which a resilient packing is employed; but I do not claim a resilient packing or connection broadly.

It is the object of my present invention to overcome an objection to such construction as is shown in the said patent, which when the limit of movement of the resilient packing is reached directs the strain upon the frangible material of which the bowl is made. On the contrary, the yielding connection between the seat and bowl of my device is unlimited by the frangible material, and under 45 a less strain than will chip the bowl an

tire detachment of the parts will be effected, there being two distinct yielding connections, the first by the yielding of the rubber pad and, second, by the separation of the brackets 12 from the plates 18 under a strain greater than can be resisted by the pad.

I do not limit myself to the details of construction herein shown and described, but reserve the right to modify and vary the same within the scope of my invention. 55

What I claim is—

1. The combination with a water-closet seat and bowl, of a flat resilient pad upon the side of the bowl, and mechanism connecting the seat with the face of the pad, whereby the pad is compelled to yield edgewise under pressure substantially as specified. 60

2. The combination with a water-closet bowl and seat, of pads upon the bowl, depending brackets upon the seat, plates intermediate of the brackets and pads, and mechanism carried by the brackets for securing them to the plates and for pressing the plates tightly against the pads, substantially as specified. 65

3. The combination with a water-closet bowl and seat, of yielding plates carried by the bowl and provided with lugs, brackets depending from the seat and provided with recesses designed to be engaged by the lugs of the yielding plates, and mechanism for securing the brackets to the plates, substantially as specified. 70

4. The combination with a bowl and projections thereon, of opposite recesses therein, lug-plates, and lugs in the recesses, a cushion or pad in each of the recesses, a seat and brackets secured thereto, and abutment-screws carried in the brackets, substantially as and for the purpose specified. 80

In testimony of all which I have hereunto 85 subscribed my name.

JOHN C. FEBIGER, JR.
